(57) **CLAIM**

The ornamental design for a protective container, as shown and described.

DESCRIPTION

FIG. 1 is a perspective view illustrating a lightweight protective container in accordance with the present invention;

FIG. 2 is a front view illustrating the protective container of the invention;

FIG. 3 is a rear view illustrating the protective container of the invention;

FIG. 4 is a side view illustrating the protective container of the invention;

FIG. 5 is a side view illustrating the protective container of the invention;

FIG. 6 is a top view illustrating the protective container of the invention;

FIG. 7 is a bottom view illustrating the protective container of the invention;

FIG. 8 is a perspective view illustrating a closed lid of the protective container of the invention; and,

FIG. 9 is a perspective view illustrating an interior conforming to the object placed in the protective container of the invention.

The dashed lines and/or broken line(s) of FIGS. 1-9 illustrating the hinge (FIGS. 2-5, 7, and 9), the side handles (FIGS. 1-2 and 4-9), and front latch (FIGS. 1-2 and 4-9) define the bounds of the claimed design and form no part thereof. The heavy stippling and irregular form of FIGS. 1-9 illustrates the exterior polyurea coating material in accordance with an embodiment of the present invention. The light stippling of FIG. 1 illustrates the interior foam in accordance with an embodiment of the present invention.

1 Claim, 9 Drawing Sheets
